[57] CLAIM

The ornamental design for a finger puppet, as shown and described.

DESCRIPTION

FIG. 1 is a perspective view of a finger puppet, showing my new design in use;

FIG. 2 is another perspective view of the design in use;

FIG. 3 is a top plan view thereof;

FIG. 4 is a front elevational view thereof;

FIG. 5 is a left side elevational view thereof;

FIG. 6 is a right side elevational view thereof;

FIG. 7 is a rear view thereof;

FIG. 8 is a bottom plan view thereof;

FIG. 9 is a top plan view of a second embodiment of the design in FIG. 1;

FIG. 10 is a front elevational view thereof;

FIG. 11 is a left side elevational view thereof;

FIG. 12 is a right side elevational view thereof;

FIG. 13 is a rear elevational view thereof; and,

FIG. 14 is a bottom plan view thereof.

The broken lines in FIGS. 1, 2, 10, and 13 are for illustrative purposes only, and form no part of the claimed design.
